(57) **CLAIM**

The ornamental design for a complex dielectric sensor as shown and described.

DESCRIPTION

FIG. 1 is a perspective view of a complex dielectric sensor. FIG. 2 is a top view of the complex dielectric sensor of FIG. 1.

FIG. 3 is a left side view of the complex dielectric sensor of FIG. 1.

FIG. 4 is a front side view of the complex dielectric sensor of FIG. 1.

FIG. 5 is a right side view of the complex dielectric sensor of FIG. 1.

FIG. 6 is a rear side view of the complex dielectric sensor of FIG. 1; and,

FIG. 7 is a bottom view of the complex dielectric sensor of FIG. 1.

The broken lines in the figures are shown for the purpose of illustrating the environment or boundaries of the complex dielectric sensor and form no part of the claimed design.
